UNITED STATES PATENT OFFICE.

HENRY D. HIBBARD AND WALTER GASTON, OF PLAINFIELD, NEW JERSEY,
 ASSIGNORS TO MANGANESE STEEL SAFE COMPANY, OF NEW YORK,
 N. Y., A CORPORATION OF NEW JERSEY.

VAULT OR SAFE.

SPECIFICATION forming part of Letters Patent No. 758,069, dated April 26, 1904.

Application filed February 11, 1903. Renewed September 22, 1903. Serial No. 174,230. (No model.)

To all whom it may concern:

Be it known that we, HENRY D. HIBBARD and WALTER GASTON, citizens of the United States, residing at Plainfield, in the county of Union and State of New Jersey, have invented 5 certain new and useful Improvements in Vaults or Safes, of which the following is a specification.

This invention relates to safes or vaults, the 10 object of the invention being to provide an improved structure in which the fastening means shown and described in the several Letters Patent granted to Henry D. Hibbard for vaults, particularly Patents Nos. 662,433, dated 15 November 17, 1900; 679,371, dated July 30, 1901, and 713,880 and 713,881, dated November 18, 1902, may be used to greater advantage and without interfering with the capacity of the safe.

20 In the drawings accompanying and forming part of this specification, Figure 1 is a horizontal sectional view of a pair of safe or vault plates organized to form this improved structure. Fig. 2 is an interior elevation thereof. 25 Fig. 3 is a view similar to Fig. 1, showing a somewhat different form of means for maintaining the plates in alinement. Fig. 4 is an interior elevation thereof. Fig. 5 is a vertical sectional view, partly in elevation, taken 30 in the line *a a*, Fig. 3.

Similar characters of reference indicate corresponding parts throughout the different figures of the drawings.

The fastening means referred to is particularly adapted for use with what is ordinarily known as "unmachinable" plates—that is, plates—such, for instance, as manganese steel plates—which it is not practicable to drill or cut to form bolt-openings for the reception of 35 bolts and by means of which fastenings the wall components or plates will have their contiguous edges or faces brought together under considerable tension, thereby obtaining high initial resistance, which must first be overcome 40 before such plates can be separated.

One of the objects of the present improvement is the provision of a structure in which the fastening means are so located that the

capacity of the safe or vault is not interfered with.

Another object of the invention is the organization of the fastening means in such manner that a part thereof will, in addition to performing its usual function, assist in reinforcing the companion part of such fastening means, 55 should this for any purpose be necessary.

Another object of the invention is the provision of a wall component or plate having an interiorly-located recess and an exteriorly-located bead.

In the patented structures hereinbefore referred to the projections formed at the edges of the plate or wall components around which the links were located extended interiorly of the safe to such an extent that they somewhat 65 interfered with the capacity of the safe or vault, especially when a large number thereof were used, thus interfering with the interior arrangement of the shelving and compartments and preventing the utilization of all the 70 space, necessitating that such shelving, which otherwise would be continuous from side to side of the structure, be arranged in sections. In order to obviate this disadvantage when the capacity of the safe or vault is a material 75 consideration, the present improved structure is provided, in which the safe or vault plates are so constructed that while using the same fastening means such fastening means are located out of the way, so as not to interfere 80 with the interior area of the vault, and for this purpose we form in the structure shown each of the plates 2 at the inner side of the projections 3 with a longitudinally-extending recess, whereby provision is made for locating 85 the links around the projections in the proper manner without materially interfering with the depth of such projections. It will be obvious, of course, that these recesses need not extend the entire length of the plates, but 90 could be made to conform to the ends of the links at the sides of the projections. By this organization the inner ends 5 of the projections may be flush with the major portions 6 of the plates, so that they will not extend beyond 95 the inner wall-surfaces of the safe or

vault, and thus not interfere with the interior arrangement of the structure. If for any reason, however, it should be desirable that the 5 projections extend beyond such inner wall-surfaces, by the provision of these recesses the projections need only project a comparatively short distance beyond the wall-surfaces of the plates, so that by the cutting of slight recesses in the inner edges of the shelving the 10 arrangement of such shelving need not be interfered with. In forming these recesses during the casting of the plates each plate may be given a substantially ogee surface formation both at its interior and exterior. Each 15 plate will in practice be usually provided with an external bead or projection 7 at its outer surface adjacent to the joint, which in the form of the plate shown is a longitudinal bead and which constitutes, in the manner 20 set forth in said Patent No. 679,371, hereinbefore referred to, and in Patent No. 662,428, dated November 27, 1900, a means to prevent the opening of the joint by the action of explosives. The alinement of the plates is 25 maintained by a key 8, similar to that shown and described in said patents, being located in an opening 9, formed by contiguous recesses in the meeting walls of the projections. This key, however, may be inserted into position 30 after the links have been located upon the projections, and for this purpose the opening 9' will be located somewhat nearer the ends of the projections, Figs. 3, 4, and 5, and at the outer side of such links.

35 In the forms shown in Figs. 3, 4, and 5 the key is shown wedge-shaped, the opening 9' being tapered at its outer side to receive the key, so that the key can extend, if for any reason it should be desirable, beyond the 40 projections and overlap the clamping member, each of which in the form shown comprises a ring or link 13, preferably shrunk onto each pair or set of registering projections. In the present instance the projections in 45 which the tapered or wedge-shaped key is located are shown projecting somewhat beyond the inner surfaces of the plate, although this need not necessarily be the case.

Having thus described our invention, we 50 claim—

1. A safe or vault plate having one or more projections along its edge and at the inner side of such projection or projections a recess.
2. A safe or vault wall component having 55 adjacent to its edge on the interior thereof a recess and on its exterior contiguous to its edge, a bead.
3. A safe or vault plate having a plurality of projections along its edge on the interior 60 thereof, and at the inner side of such projections a longitudinally-extending recess.
4. A safe or vault plate having a plurality of projections along its edge on the interior thereof, and at the inner side of such projections a longitudinally-extending recess said 65

plate having at its outer side a longitudinally-extending bead.

5. A safe or vault plate having one or more projections along its edge on the interior thereof, the inner end face of each being substantially flush with the wall-surface of the plate. 70

6. A safe or wall plate having interiorly-located projections adjacent to its edge and an ogee formation contiguous to such projections. 75

7. In a safe or vault, a pair of plates set edge to edge, each having one or more interiorly-located projections adjacent to its edge, the projection of one plate registering with that of its companion plate, and each of said plates 80 having a recess adjacent to its projection, whereby the inner faces of such projections are substantially flush with the major part of the interior surfaces of the plates, and means for securing said projections together. 85

8. In a safe or vault, a pair of plates set edge to edge each having one or more interiorly-located projections adjacent to its edge, the projection of one plate registering with that of its companion plate, and each of said plates 90 having a recess adjacent to its projection, whereby the inner faces of such projections are substantially flush with the major part of the interior surfaces of the plates, and means for securing said projections together, said 95 means comprising a shrunk-on-link.

9. In a safe or vault, a pair of plates set edge to edge each having one or more interiorly-located projections adjacent to its edge, the projection of one plate registering with that of its companion plate, and each of said plates 100 having a recess adjacent to its projection, whereby the inner faces of such projections are substantially flush with the major part of the interior surfaces of the plates, and means 105 for securing said projections together, said means comprising a shrunk-on-link, and means for maintaining the alinement of said plates relatively to each other.

10. In a safe or vault, a pair of plates set 110 edge to edge each having one or more interiorly-located projections adjacent to its edge, the projection of one plate registering with that of its companion plate, and each of said plates 115 having a recess adjacent to its projection, whereby the inner faces of such projections are substantially flush with the major part of the interior surfaces of the plates, and means for securing said projections together, said means comprising a shrunk-on-link, and means 120 for maintaining the alinement of said plates relatively to each other, said means comprising a key located in contiguous recesses formed in such projections.

11. In a safe or vault, a pair of plates set 125 edge to edge each having an interiorly-located projection or projections adjacent to its edge, the projections of one plate registering with that of its companion plate, and having its end face substantially flush with the interior wall 130

of such plate, and means for maintaining said plates in engagement.

12. In a safe or vault, a pair of plates set edge to edge, each having an interiorly-located 5 projection or projections adjacent to its edge, the projection of one plate registering with that of its companion plate and having its end face substantially flush with the interior wall of such plate, means for maintaining such 10 plates in engagement, and means for maintaining said plates in alinement.

13. In a safe or vault, a pair of plates set edge to edge, each of said plates having adjacent to its edge one or more inwardly-extend- 15 ing projections, the projections of one plate registering with those of the other, a link shrunk onto each set of registering projections, a tapered recess formed in each set of registering projections, and a wedge-shaped 20 key located in such recess and adapted to have its ends overlap the link.

14. In a safe or vault a pair of plates set edge to edge, each of said plates having a plurality of projections, the projections of one 25 plate registering with those of the other, and each of said plates having a longitudinally-extending recess at the inner sides of its pro-

jections; links located in said recesses and shrunk onto said projections, each set of projections having a tapered recess extending 30 therethrough and a tapered key projecting into each of such recesses.

15. In a safe or vault a pair of plates set edge to edge each of said plates having adjacent to its edge one or more projections, the 35 projections of one plate registering with those of another, means for clamping said plates together and means having a part projecting beyond such projections for maintaining the alinement of said plates. 40

16. In a safe or vault, a pair of plates set edge to edge, each of said plates having adjacent to its edge one or more projections, the projections of one plate registering with those of another, a link shrunk onto each set of 45 registering projections, and means projecting beyond each set of projections for maintaining the alinement of the plates, said means having a part overlapping said link.
